his ATTORNEYS

UNITED STATES PATENT OFFICE.

HUGH M. ROSS, OF WOODHAVEN, NEW YORK, ASSIGNOR TO ADRIANCE MACHINE WORKS, INC., OF BROOKLYN, NEW YORK, A CORPORATION OF NEW YORK.

BOTTLE-SEALING APPARATUS.

Application filed July 19, 1920. Serial No. 397,220.

To all whom it may concern:

Be it known that I, HUGH M. Ross, a citizen of the United States, residing at Woodhaven, in the county of Queens and State of New York, have invented new and useful Improvements in Bottle-Sealing Apparatus, of which the following is a specification.

My invention relates to bottle sealing machines and more particularly to a part of, or appliance for, such machines whereby the skirts of the usual bottle caps are forced inwardly into locking engagement with the heads of the bottles. The invention comprises a device forming a throat into which the heads of the bottles are passed so that by the engagement of the inner wall of the throat with the skirts of the caps the latter are secured in position upon the bottles. As bottle heads are not of equal size and are sometimes off center or eccentric and as the caps are variable in thickness and pliability, it is necessary for efficient action not only that the throat be adapted to be enlarged by the bottle heads and caps under a sufficient predetermined pressure but also that the various peripheral portions of the throat be independently yieldable under such pressure.

The object of my invention is to provide a sealing device which complies with these requirements.

Another object of my invention is to provide a device of the character referred to which can be manufactured of superior quality at a comparatively low cost and which will maintain efficiency with extended use.

In order that the invention may be more clearly understood, attention is hereby directed to the accompanying drawing forming a part of this specification and illustrating two forms of the invention.

In the drawing,

Fig. 1 is a vertical sectional view showing a portion of a bottle sealing machine provided with my invention, the head of the machine being raised or in operative position.

Fig. 2 is a like view of the same parts, showing the parts in the positions occupied thereby as the throat forming device is beginning its movement over the cap.

Fig. 3 is a like view of the same parts showing the bottle head and cap within the

throat forming device, and with the cap secured in sealing position on the bottle head.

Fig. 4 is a plan view of one form of throat forming device detached from the machine.

Fig. 5 is a central vertical sectional view of same.

Fig. 6 is a plan view of another form of the throat forming device; and

Fig. 7 is a central vertical sectional view of same.

As shown in the drawings, the throat forming device, which is designated generally by the letter *a*, is carried in fixed position by the head *b*, which is movable vertically with respect to the frame *c* of the machine. The caps *d* are adapted to be fed laterally into operative position through a channel *e* in the head *b*. The head is provided with a plunger *f* which is adapted to bear upon the caps during the sealing operation and to be forced upwardly against the pressure of spring *g* to permit the throat forming device to pass over the bottle head and cap. As this invention is limited to the throat forming device no further description will be given of the rest of the sealing machine, this type of machine being well-known in the art.

Referring to Figs. 4 and 5, the throat forming device comprises a plurality of segments 1, preferably made of hard metal, forming a ring which is herein designated as the throat forming ring. The rear faces of these segments are formed adjacent the top and bottom thereof with inclined surfaces, the upper of these surfaces being inclined downwardly and inwardly, as shown at 2, and the lower being inclined upwardly and inwardly, as shown at 3.

The surfaces 2 and 3 are engaged by correspondingly inclined surfaces of an upper ring 4 and a lower ring 5 respectively. These rings surround the segments 1 and are movable towards each other to permit the expansion of the throat forming ring from its normal position, the movement of the rings 4 and 5 towards each other being resisted by springs 6 coacting with opposite faces of said rings 4 and 5. The latter rings are formed of hard material, preferably metal. A cylindrical casing 7, preferably of metal, surrounds the rings 4 and 5 and springs 6 and serves to retain the various

parts in position. The rings 4 and 5 are slidable in this casing longitudinally of the axis of the device.

The segments 1 are desirably beveled off or tapered at the ends of the inner surface of the throat, as shown at 8, to facilitate the passage of the throat over the bottle head and cap. In use as the throat forming device passes over the bottle head and cap, as shown in Fig. 2, the skirt of the cap *d* is first engaged by the surface 8 and as the said device passes down further, the bottle with the cap thereon passes into the throat and the skirt of the cap is forced inwardly. When the bottle head and cap have passed completely into the throat, as shown in Fig. 3, the skirt of the cap has been forced down into sealing position. It will be seen that even when the bottle head and cap are of abnormally large size, the segments 1 are moved outwardly automatically during the capping operation against a predetermined pressure, the rings 4 and 5 being forced towards each other by the wedging action of the coacting surfaces of segments 1 and rings 4 and 5 against the pressure of spring 6. It will also be seen that when the bottle head is off center or eccentric, the segments on one side are movable outwardly independently of the segments on the opposite side of the device. While the segments yield as required, a predetermined pressure is maintained upon the skirts of the bottle caps through the resistance to the yielding of the segments. As soon as the capping operation is complete, the spring 6 and the rings 4 and 5 force the segments 1 back to their original innermost position by the separation of the rings 4 and 5 and the wedge action of the said rings on the segments 1.

The form of the invention shown in Figs. 6 and 7 is provided with segments 1 and rings 4 and 5 formed and coacting with each other the same as the corresponding parts in Figs. 4 and 5. Instead, however, of employing springs to resist the movement of the rings 4 and 5 towards each other, there is provided a ring 10 of plastic resilient material, such as rubber. This ring engages the opposite faces of the rings 4 and 5 and the peripheral central portion of the throat forming ring. Casing 11 surrounds the rings 4, 5 and 10. This casing is similar to casing 7 of Figs. 4 and 5 except that it is provided with openings or perforations 12 into which the material of the ring 10 is adapted to be forced by a movement of the rings 4 and 5 towards each other. The amount of pressure exerted by the ring 10 on the rings 4 and 5 can be varied by variations in size and number of the openings or perforations 12.

While I have shown two forms of my invention, it is to be understood that many changes may be made in the forms of in-

vention shown without departing from the spirit of the invention.

Having thus described my invention, what I desire to secure by Letters Patent of the United States is:

1. A closure sealing device comprising a throat forming ring having a plurality of segments movable relatively to each other to permit enlargement of the ring, and means 70 yieldingly resisting such movement comprising a member movable on said segments to contract the ring, and means tending continuously to so move said member.

2. A sealing head provided with a closure sealing device comprising a throat forming 80 ring adapted to receive a bottle with a cap thereon and having a plurality of segments movable relatively to each other to permit enlargement of the ring by the cap, and means yieldingly resisting such movement 85 comprising a member movable on said segments to contract the ring, and means carried by the head and tending to move said member in said direction while the bottle with the cap thereon is in the throat forming 90 ring.

3. A sealing head provided with a closure sealing device comprising a throat forming ring adapted to receive a bottle with a cap 95 thereon and having a plurality of segments movable relatively to each other to permit enlargement of the ring by the cap, and means yieldingly resisting such movement comprising a member movable relatively to said segments, said member and segments 100 having coacting surfaces inclined to the direction of relative movement between them whereby said member is adapted upon the movement thereof in a given direction to contract the ring, and means carried by the 105 head and tending to move said member in said direction while the bottle with the cap thereon is in the throat forming ring.

4. A closure sealing device comprising a 110 throat forming ring having a plurality of segments movable relatively to each other to permit enlargement of the ring, and means yieldingly resisting such movement comprising a second ring movable along 115 said segments to contract the throat forming ring, and means tending continuously to so move said second ring.

5. A sealing head provided with a closure sealing device comprising a throat forming ring adapted to receive a bottle with a cap 120 thereon and having a plurality of segments movable relatively to each other to permit enlargement of the ring by the cap, and means yieldingly resisting such movement comprising a second ring movable relatively to said segments, said member and segments having coacting surfaces inclined 125 to the direction of relative movement between them whereby said second ring is adapted upon the movement thereof in a 130

given direction to contract the throat forming ring, and means carried by the head and tending to move said second ring in said direction while the bottle with the cap thereon is in the throat forming ring.

6. A closure sealing device comprising a throat forming ring adapted to receive a bottle with a cap thereon and having a plurality of segments movable relatively to each other to permit enlargement of the ring by the cap, and means yieldingly resisting such movement comprising a second ring movable relatively to said segments, said member and segments having coacting surfaces inclined to the direction of relative movement between them whereby said second ring is adapted upon the movement thereof in a given direction to contract the throat forming ring, and plastic means tending to move said second ring in said direction while the bottle with the cap thereon is in the throat forming ring.

7. A closure sealing device comprising a throat forming ring having a plurality of segments movable relatively to each other to permit enlargement of the ring, and means yieldingly resisting such movement comprising a plurality of members movable relatively to said segments in opposite directions longitudinally of the axis of said ring to contract said ring, and means tending to so move said members.

8. A closure sealing device comprising a throat forming ring having a plurality of segments movable relatively to each other to permit enlargement of the ring, and means yieldingly resisting such movement comprising a plurality of segment positioning rings surrounding said segments and movable relatively to said segments in opposite directions longitudinally of the axis of said throat forming ring to contract said throat forming ring, and means tending to so move said segment positioning rings.

9. A closure sealing device comprising a throat forming ring having a plurality of segments movable relatively to each other to permit enlargement of the ring, and means yieldingly resisting such movement comprising a plurality of segment positioning rings surrounding said segments and movable relatively to said segments in opposite directions longitudinally of the axis

of said throat forming ring to contract said throat forming ring, and resilient means 55 arranged between said segment positioning rings and tending to move the same in said opposite directions.

10. A closure sealing device comprising a throat forming ring having a plurality of segments movable relatively to each other to permit enlargement of the ring, and means yieldingly resisting such movement comprising a plurality of segment positioning rings surrounding said segments and movable relatively to said segments in opposite directions longitudinally of the axis of said throat forming ring to contract said throat forming ring, and resilient plastic material arranged between said segment 70 positioning rings and tending to move the same in said opposite directions.

11. A closure sealing device comprising a throat forming ring having a plurality of segments movable relatively to each other 75 to permit enlargement of the ring, and means yieldingly resisting such movement comprising a plurality of segment positioning rings surrounding said segments and movable relatively to said segments in opposite directions longitudinally of the axis 80 of said throat forming ring to contract said throat forming ring, and a casing surrounding the aforesaid parts.

12. A closure sealing device comprising a 85 throat forming ring having a plurality of segments movable relatively to each other to permit enlargement of the ring, and means yieldingly resisting such movement comprising a plurality of segment positioning rings surrounding said segments and movable relatively to said segments in opposite directions longitudinally of the axis 90 of said throat forming ring to contract said throat forming ring, resilient plastic material arranged between said segment positioning rings and tending to move the same 95 in said opposite directions, and a casing surrounding and engaging said segment positioning rings and said material and provided with openings into which the material is adapted to be forced.

In testimony whereof, I have signed my name to this specification.

HUGH M. ROSS.
